UNITED STATES PATENT OFFICE.

WILLIAM HOFFMAN, OF SOLANO COUNTY, CALIFORNIA.

FROG FOR BAYONET-SCABBARDS.

Specification of Letters Patent No. 28,175, dated May 8, 1860.

To all whom it may concern:

Be it known that I, WILLIAM HOFFMAN, of the county of Solano and State of California, have invented a new and Improved 5 Joint-Frog for Bayonet-Scabbards; and I do hereby declare that the following is a full, clear, and exact description of the construction and operation of the same, reference being had to the annexed drawings, 10 making a part of this specification.

The nature of my invention consists in making the frog of two parts which are united by a bolt or other equivalent device; the one receives the bayonet scabbard, and is 15 made up of the shank and ear; and the other is the loop through which the waist belt passes; the whole being made of leather or like material.

The drawings, herewith, show the parts of 20 the frog; No. 1, being a perspective view, and No. 2 a shaded projection.

A, B, C, D is the shank; B, D, E, the ear, and F, G, H, I, the loop.

The two parts are connected together by 25 a bolt or key, M, passing through the ear, and through the front side of the loop, to which the bolt is secured by being riveted to a metal plate attached to the inside of the

loop by rivets or stitches. The ear turns freely on the bolt, and it may have, on its outside, a metallic plate, K, L, for the bolt to pass through, for ornament, and to give greater durability. By this arrangement, the mouth of the scabbard is brought nearly on a level with the top of the waist belt. 35

The advantages of this invention, are: the swinging of the bayonet and scabbard, in rapid movements, is prevented; and much consequent wear and tear is avoided; the bayonet is held close to the person, and is 40 not so liable to fall from the scabbard; and when the wearer sits down, the scabbard is readily turned out of the way and is not liable to be broken.

What I claim as my invention and desire 45 to secure by Letters Patent, is—

Making the frog of the bayonet scabbard in two parts as described, when the said parts are united together by a bolt or other equivalent device substantially in the manner and for the purpose set forth. 50

W. HOFFMAN.
